UNITED STATES PATENT OFFICE.

DAVID E. SMITH, OF CHICAGO, ILLINOIS.

CARD GAME.

Application filed October 7, 1925. Serial No. 61,123.

To all whom it may concern:

Be it known that I, DAVID E. SMITH, a citizen of the United States, and a resident at the city of Chicago, in the county of 5 Cook and State of Illinois, have invented certain new and useful Improvements in Card Games, of which the following is a specification.

My invention relates to playing cards, 10 and to card games generally, but particularly to card games of the simpler kind suitable to be indulged in without serious mental exertion with the object of affording diversion, relaxation and amusement to the 15 older players, and simple enough for the very young to understand and play, with the object of being amused, entertained and providing such training, practice, experience and education as may be derived there- 20 from.

With the above, and other objects in view, which will more particularly appear from the following description, I have described and illustrated in the following specification 25 and accompanying illustrations, one style of my said game cards, which is the style preferred by me, but it will be apparent that minor variations may be made therein, without departing from the spirit of my said 30 invention.

In the accompanying drawings, in which like numerals of reference refer to the same parts throughout the various views,

Figure 1 is a view of one of the "word cards" showing the picture of a "cow" with the words "Moo-oo" thereon.

Figure 2 is a view of one of the "word cards" showing a "donkey" with the words "Hee-haw" thereon.

Figure 3 is a view of one of the "word cards" showing the picture of a "cat" with the words "Meow" thereon.

Figure 4 is a view of one of the "word cards" with the picture of a "duck" with the words "Quack" thereon.

Figure 5 is a view of one of the lesser suit cards, showing a picture of one of the animals, as the "donkey" with the numerals "2" and "2" thereon.

In the preferred form of my said game cards, as illustrated in the drawings herein, I employ a pack of playing cards of the usual size and shape, and containing preferably 41 cards of a character as partially shown in the said drawings. The said forty-one cards comprise four different suits, of

ten cards each, and one blank card for the "joke" or "joker card" as hereinafter explained.

It is desirable that the backs of all the 60 cards in the deck shall be of a uniform design and color, or the said backs may be blank, if desired, the principal purpose of having them uniform is to prevent the possibility of identifying any particular card by 65 the marking on the back thereof.

On the face, or front sides of four of the cards, I have provided the pictures as shown in Figures 1, 2, 3, and 4, with the words as shown, to indicate the sound made by each 70 animal thereon represented, viz, one bears the picture of a "cow" with the words "Moo-oo", a second bears the picture of a "donkey" with the words "Hee-haw"; a third bears the picture of a "cat" with the words 75 "Meow"; while the fourth bears the picture of a "duck" with the words "Quack" thereon. These four cards are known as the "word-cards" and largely take the place of the "ace" cards in other card games, as will 80 be hereinafter more particularly described. While I have repeated the said words four times, it will be apparent that it would serve equally well if said words were placed thereon fewer or more times, as they are merely 85 indicative of the "word cards" of each suit as hereinafter explained.

Thirty-six of the remaining cards of the pack are divided into four suits of nine 90 cards each, to correspond to the four "word cards." Each one of the nine cards in each suit, has a picture of the animal representing such suit printed thereon, and the nine cards of each suit are numbered consecutively from two to ten, both inclusive, the 95 numerals indicating such numbers appearing preferably in the upper left hand corner and in the lower right hand corner, reversed, in such manner that they may be conveniently read without regard as to 100 which end of said card is uppermost, preferably as shown in the card shown in Fig. 5, all of the other suit cards being substantially the same as the one there shown, with suitable change of picture and numerals. 105

Although the cards herein described may be employed equally well if printed all in one uniform color of ink, yet for convenience, and to distinguish one suit quickly and readily from another suit, I have preferably 110 made each 10 suit cards of a different color from each other set of suit cards, as red

for the "moo-oo" card suit, purple for the "hee-haw" card suit; blue for the "meow" card suit, and green for the "quack" card suit.

- 5 One card, being the 41st, I preferably leave blank, to permit the players to write thereon such phrase or joke as such players shall prefer, such as "I love you", "Kiss me", "Take me home" or any other phrase or 10 joke which may provide amusement, or fun. If preferred, the joker card may be omitted, and games played without it.

In playing with my said cards, the dealer shuffles the cards, and places them face down 15 in the middle of the table. Any number from two to six may take part in the play, as desired. To secure the hands for play, each player draws a card in rotation, commencing with the player at the left of the 20 dealer, and continuing around the table to the left. When a "word card" is drawn by any player, that suit is trump for that hand, and the drawing stops when it reaches the dealer. The player drawing the "word card" 25 should call it out at once, because if he does not, and a succeeding player draws another "word card" and calls it out first, his card becomes trump, and the first player loses his opportunity of naming trumps. In playing 30 the hands, the player drawing the "word card" which is trump, must play it first. After this trick is taken, any suit may be led. The player taking the trick has the lead in the next trick, and the other players 35 must follow suit, if they have suit cards, or must trump. The highest suit card, or trump card takes the trick. The "word card" is the low card of the suit. In counting 40 points, each trick taken counts for one point. The player drawing a "word card" which is trumps, scores five points, and the player taking a trick with a "word card" trump counts six points.

When the blank card is used, it becomes a 45 trump of all suits played, but the lowest in the game.

It will be apparent that many variations in the animals employed may be used, and that many different rules may be formulated 50 for playing said game, and that said cards

may be used to play many various games which the ingenuity of the players may suggest, and that each and all of such variations in design, and play are within the scope and spirit of my said invention. 55

Having thus described my said invention, what I claim and desire to secure by Letters Patent, is the following, viz:—

1. A deck of cards for playing the game of "Hee-Haw" said cards and game being 60 designed to depict certain well known animals, and comprising four "word cards" each bearing a picture of a different animal, and thirty-six suit cards, nine bearing the representation of each of said animals, and 65 numbered consecutively from two to ten, both inclusive, substantially as shown, and for the purposes described.

2. A deck of cards for playing the game of "Hee-Haw", said cards and game being 70 designed to depict certain well known animals, said deck comprising four suits of ten cards each, one card of each suit having a representation of the animal representing said suit, and words to indicate said animal, 75 and the other nine cards of each of said suits having a representation of said animal, but no words, said other nine cards in each suit being numbered consecutively from two to ten, both inclusive, substantially as shown 80 and for the purposes described.

3. A deck of 41 playing cards for playing the game of "Hee-Haw", one of said cards being blank, and adapted to be written upon, and in play intended to be trumps of any 85 suit which is trump, four suits of ten cards each, each ten cards of each suit bearing a representation of some member of the animal kingdom, nine of said cards bearing numbers from two to ten consecutively, and one of 90 each of said suit cards bearing words to remind players of the animal represented, said word cards indicating the trumps in play with said cards, substantially as shown and described. 95

In testimony whereof, I have hereunto affixed my signature at the city of Chicago, State of Illinois.

DAVID E. SMITH.
